UNITED STATES PATENT OFFICE.

THOMAS MADDOCK, OF NEW YORK, ASSIGNOR TO HENRY MADDOCK, OF BROOKLYN, NEW YORK.

DESIGN FOR A DISH.

SPECIFICATION forming part of Design No. 19,201, dated July 9, 1889.

Application filed September 8, 1888. Serial No. 284,933. Term of patent 7 years.

To all whom it may concern:

Be it known that I, THOMAS MADDOCK, a subject of the Queen of Great Britain, and a resident of the city of New York, in the county 5 and State of New York, United States of America, have invented or produced a new and original Design for Covered Dishes, of which the following is a specification, reference being had to the accompanying photographs, forming part hereof.

This design relates to covered dishes, such as tureens, vegetable-dishes, &c.

My design pertains to the surface ornamentation of the covers and bodies of dishes, and to 15 the shape and surface ornamentation of the handles of dishes and the covers, as will be described in detail hereinafter.

The leading features of my design are a flat band around the edge of the cover of a dish, 20 such band extending from the termination of the convex portion of the cover to the outer edge of the cover, and a frill or fluted ornamentation upon such flat band; also, such a flat band on the cover of a dish, so that the 25 outline of the inner edge of such band is of the same outline as the outer edge of the cover, whereby the terminating line of the convex portion of the cover corresponds approximately in contour with the outer edges 30 of the cover; also, a band or frill of fluted ornamentation on the lower portion of the dish and raised slightly beyond the surface of the dish proper, such band beginning directly above the foot or standard of the dish and 35 extending upwardly to a distance about equal to the width of the band upon the cover of the dish; also, in a handle for dishes or covers, such a handle having the shape of a reversed letter **S**, the central portion of which is of 40 greater thickness than the ends and is ornamented with a series of scales appearing to lap one over the other, and the ends of which handle terminate in the form of a leaf set upon the body or cover.

45 In the accompanying photographs, Figure 1 is a perspective view looking at a dish and cover from an angle slightly above the left-hand corner of the dish, showing my new design thereon; and Fig. 2 is an end elevation 50 of such a dish and cover.

Referring to the photographs, let A repre-

sent the cover of the dish; B, the body, and C C the handles.

a is the flat band surrounding the outer edge of the cover, and b is the convex portion 55 of the cover.

c is the band of fluted ornamentation on the lower portion of the dish, and d is the ordinary foot or standard of the dish.

e f are the central portions of the handles 60 C C, and g g are the extremities of the handles C C.

h h indicate the corners of the dish.

The cover A is convex or swelled in its central portion, and this convexity, near the edge 65 of the cover, is ended by the flat band a, which intervenes between the convex portion b and the edge of the cover. Thus a flat space is formed around the outer part of the cover, and as this flat band or space a is made of 70 equal width around all the edges of the cover the outline of the convex portion b of the cover is the same as that of the edge of the cover. To give this flat band a a finished and ornamental appearance, a flute or frill is 75 formed upon it, such as shown in the photographs. The effect of this flat band is to give a border to the cover, whereby from the edge of the cover to the commencement of the convex portion thereof three lines are formed— 80 first, the line of the edge of the cover; second, the line of the edge of the fluted ornamentation, and, third, the line of the termination of the convex portion. These three lines produce a very pleasing effect, especially if the 85 outline of the dish is of a somewhat varied shape, such as that shown in the photographs, wherein the sides and ends of the dish are shown as receding or curved slightly inwardly from the corner portions, and the corners are rounded in the form of arcs of two circles which meet with a re-entering angle at h h, as seen in Fig. 1, thus giving the corner 90 a scalloped appearance.

As the flat band a is of equal width throughout its circuit of the cover, its outline and the line of termination of the convex portion b will have the same scalloped contour as the edge of the cover.

The body B of the dish has at its upper portion and maintains throughout its lower portion the scalloped contour just described in 100

regard to the cover. The body is swelled outwardly in a graceful curve slightly below the cover, and then the walls recede toward the base at an angle of about sixty degrees, so that 5 the foot or standard of the dish is considerably smaller than the top or cover portion. This will be seen best in Fig. 2. The foot or standard *e* of the dish is slightly swelled from the line of descent of the walls of the dish, 10 and at the point where it meets the walls the slightly-projecting band or frill *e* of fluted ornamentation begins. This band *e* extends upwardly from the standard *e* to a distance about equal to the width of the flat band *a* on the 15 cover A. The flutes upon this band *e* extend upward toward the top of the dish and are of the same style of ornamentation as that used in the flat band *a* of the cover.

The handles C C, having approximately the 20 shape of a reversed letter S, are enlarged or thickened in their centers and diminish in size toward their ends, which taper off in the form of a leaf, which rests upon the part of the dish to which the handle is attached. I 25 ornament the central portion of the handles

by a scale-like figure, whereby the surface has the appearance of a number of little scales lapping one over the other, as will be seen at *ff*. The ends of the handles C C terminate against the dish in leaf-like figures, 30 as shown.

What I claim is--

1. In a design for a covered dish, the shape and surface ornamentation thereof, substantially as shown in the accompanying photographs. 35
2. In a design for a covered dish, the surface ornamentation thereof, substantially as shown in the accompanying photographs.
3. The design for dishes having the shape 40 as shown and described, and having a handle of the shape as shown and described.

In witness whereof I have hereunto signed my name in the presence of two subscribing witnesses.

THOMAS MADDOCK.
